SAMUEL C. HAWKINS, OF PATCHOGUE, NEW YORK.

Letters Patent No. 85,820, dated January 12, 1869.

IMPROVED TRACE-FASTENING.

The Schedule referred to in these Letters Patent and making part of the same.

To all whom it may concern:

Be it known that I, SAMUEL C. HAWKINS, of Patchogue, in the county of Suffolk, and State of New York, have invented a new and improved Trace-Fastening; and I do hereby declare that the following is a full, clear, and exact description of the same, reference being had to the accompanying drawing, forming a part of this specification.

This invention consists in the providing of the forward extremity of the trace with a spring-catch, and the construction of the tug with suitable recesses under its loop for reception of said catch, whereby, when the end of the trace is inserted into the loop, the said spring-catch will lock into one of the said recesses of the tug, thereby effecting a convenient and durable fastening.

It also consists in the arrangement, in combination therewith, of a locking-slide, for locking with a projection or lip upon the catch, whereby, by the forward sliding of the trace to the end of the loop, the catch may be locked inwardly by the forcing back of the slide, thereby enabling the trace to be easily withdrawn, when desirable, without catching in the said recesses.

Referring to the accompanying drawing—

Figure 1 represents a longitudinal section of a trace and tug provided with a fastening constructed according to my invention;

Figure 2 represents a side view of the forward portion of a trace, with my invention attached thereto, detached from the tug; and

Figure 3 represents a detached portion of the locking parts of the tug.

Similar letters of reference indicate corresponding parts in the several figures.

A is a trace, held within the loop of a tug, B, and differing in no substantial particular from a trace of ordinary construction, except that, instead of having holes for reception of the tongue of the tug-buckle, it has riveted to and projecting from its forward extremity a metallic plate, a.

Within this plate a is cut, in a longitudinal direction, a slot which, on one side of said plate, is surrounded above and below and in front with an outwardly or laterally-projecting wall, c.

Pivoted at a point, x, within the space enclosed by this wall c, and with its locking-end projecting through said longitudinal slot, is a catch, d.

Said catch d is operated by a spring, f, and is constructed and arranged for hanging when backwardly drawn, but offering no obstruction when the trace is being forced into the loop.

e is a projection or shoulder provided upon the rear or locking-extremity of the catch d, for preventing said catch from being forced by the spring too far through the slot.

The said spring f may be of any suitable form for effecting the purpose for which it is designed, but is preferably of a form and arrangement, as represented in those parts of fig. 2 which are represented by the said letter f, so that while it is held firmly in place by the pivot x, its extremities, by entering the rear open

end of the wall c, may press upon the catch d, while the central portion, or opposite doubled extremity thereof, may serve to hold in place a locking-slide, g, pivoted at the forward end of the plate a.

Said locking-slide g is so arranged that, by its backward sliding when the spring-catch d is inwardly forced, the rear end of said slide will lock with a projection or lip, i, of the said catch, thereby holding said catch in that position, so that it may be easily withdrawn from the loop without hanging therein.

The tug-strap B resembles in outward appearance the ordinary tug-strap without the trace-buckle, but is internally provided, at different points under its loop b, with recessed or notched plates h, each having an opening or locking-recess, o, and one of which is represented detached from the tug-strap in fig. 3.

Said plates h are longitudinally arranged between the layers of leather composing the tug-strap B, and with their recesses o opening into the space enclosed by the loop b, so that when the trace A is forced under the loop, its spring-catch d will hang within one of the said recesses or openings o, as represented in fig. 1.

The ends of the plates h are more firmly secured, while the loop b is also strengthened by means of transversely-arranged metallic bands p, passing over the ends of the said plates and under the said loop.

The forward end of the loop is closed by the filling in of leather, or other material, as represented in fig. 1, so that when the trace is forced under the loop to a sufficient distance, the forward end of the locking-slide g will be brought in contact with the said closed end, and be forced to slide back within the plate a.

Said backward sliding of the locking-slide being at a time when the locking-extremity of the spring-catch d is forced within the longitudinal slot of the plate a, by the passing thereof over the solid part of the tug-strap beyond the last locking-recess, the rear end of the said locking-slide g will be made to engage with or slide over the projection or lip i of the catch d, thereby locking back the said catch within the slot, whereupon the trace A may be withdrawn from the loop without the hanging of the catch d within the locking-recesses o.

What I claim as my invention, and desire to have secured by Letters Patent, is—

1. The combination of the forward end of a trace, provided with a spring-catch, and a tug-strap, provided with corresponding locking-recesses under its loop for reception of the said spring-catch, whereby, upon the insertion of the end of the trace within the loop of the tug-strap, the spring-catch will enter one of the locking-recesses, thereby effecting a convenient and durable fastening.

2. In combination with the above, the locking-slide g and projection i, of the spring-catch d, operating substantially as and for the purpose herein set forth.

SAM'L C. HAWKINS.
